[57] CLAIM

The ornamental design for a double sided jewelry setting, as shown and described.

DESCRIPTION

FIG. 1 is an enlarged front elevation view of a double sided jewelry setting illustrating my new design, the rear elevation view being identical in appearance; FIG. 2 is a right view thereof, the left view being identical in appearance; and, FIG. 3 is a top plan view thereof, the bottom view being identical in appearance.

The broken lines showing a chain are for illustrative purposes only and forms no part of the claimed design.

FIG. 1.

FIG. 2.

FIG. 3.
